UNITED STATES PATENT OFFICE.

ALEXANDER J. RUDOLPH, OF CHICAGO, ILLINOIS.

MACHINE FOR FORMING BOTTLE-NECKS.

SPECIFICATION forming part of Letters Patent No. 631,586, dated August 22, 1899.

Application filed February 17, 1899. Serial No. 705,879. (No model.)

To all whom it may concern:

Be it known that I, ALEXANDER J. RUDOLPH, a citizen of the United States, residing at Chicago, in the county of Cook and State of Illinois, have invented certain new and useful Improvements in Machines for Forming Bottle-Necks, of which the following is a specification.

My invention relates to that class of machines for forming bottle-necks which are adapted to size, shape, and finish the exterior and interior surface of the necks of glass bottles while such necks are in a heated ductile condition.

15 The principal object of my invention is to provide a machine for forming a bottle-neck with means for adjusting its roll and forming mechanism longitudinally; and the invention consists in the features, combinations, and 20 details of construction hereinafter described and claimed.

In the accompanying drawings, Figure 1 is a side elevation of a portion of a machine, partly in section, constructed in accordance 25 with my improvements; Fig. 2, a plan view of the mechanism shown partly in section in Fig. 1; and Figs. 3 and 4 sectional detail views of the forming-plug.

30 In illustrating and describing my improvements I have only illustrated and described those portions of the mechanism which I consider to be new, taken in connection with so much that is old as will enable those skilled in the art to practice the invention, leaving 35 out of consideration other and well-known mechanisms which, if described and illustrated here, would only tend to prolixity, ambiguity, and confusion.

In constructing a machine in accordance 40 with my improvements I provide a rotatable mandrel A, which is adapted to carry all the operative parts. The front portion of this mandrel is provided with a forming-plug B, which, as shown in Figs. 1 and 2, is composed 45 of two studs b, secured to the front portion of the mandrel and connected together at their outer ends by means of an arrow-head b', each of the studs carrying a roll b''. During the rotation of the mandrel this forming-plug 50 is adapted to enter the opening in the bottle-neck and size and finish the same.

In Figs. 3 and 4 I have shown a modified

form of forming-plug, which consists of a supporting-pin C, secured in the rotatable mandrel and which at the front portion thereof is 55 provided with an arrow-head c. This arrow-head carries a number of loose rolls c', arranged at an incline, so that as they strike the material in the opening of the bottle-neck they will rotate and gradually crowd the same 60 out to meet the other mechanism, as herein-after described. The pin is provided with a loosely-rotatable shell C', which is the forming-plug proper and which will under certain conditions rotate with the material forming 65 the neck of the bottle or revolve freely therein. For instance, if the interior opening of the bottle-neck is larger than the forming-plug and but one forming-roll is used to form the exterior of the bottle-neck, this sleeve will 70 freely rotate on its supporting-pin, but if the opening of the bottle-neck be the same size as this shell and one or more forming rolls or dies be used on the exterior, then the shell will rotate with the bottle.

To size and shape the exterior of the bottle-neck, I prefer to use a pair of forming-rolls D and D', which are rotatably mounted upon parallel bars E and which have adjustable extensions made in two threaded sections e and 75 e', connected together by means of a "turn-buckle" E'. The parts are so arranged that the lock-nuts e² may be loosened and the forming-rolls moved backwardly and forwardly 80 longitudinally to provide for any-sized lip on 85 the bottle-neck. These extensions of the parallel bars operate in slots g of a rotatable disk G, which is mounted in the standard H and which permits the forming-rolls to be moved 90 toward or from the axis of the rotatable mandrel.

To assist in forming a lip on the neck of a bottle, I provide what I term a "shoulder" portion I, which has two radially-extending arms i, made integral therewith and bent backwardly at their outer ends at i', so as to extend through the disk H and backwardly 95 therefrom. To move this shoulder portion backwardly and forwardly, I provide a reciprocating disk or sleeve K, which is secured to the backwardly-extending arms of the shoulder portion, as shown particularly in Figs. 1 and 2. Helical coiled springs k surround these 100 backwardly-extending arms of the shoulder

and are interposed between the disk II and the sliding disk K, so that as the disk K moves forwardly, as hereinafter described, the shoulder is also moved forward, but when released 5 the helical springs tend to move the parts back to their normal position.

In order to operate the parts, an operating-sleeve L is slidably mounted on the rotatable mandrel, so as to rotate therewith but have 10 independent rectilinear movements. This operating-sleeve is provided with lugs L' and L'' and is connected with the parallel bars by means of the links l, so that during their forward motion the parallel bars are moved inwardly and during their backward motion are moved outwardly. During the forward movement of the operating-sleeve one of the shoulder portions is adapted to contact set-screws M in the sliding disk and move such disk, with 15 the shoulder portion, forwardly. The stop-nut N limits the backward hold of the sliding disk, and consequently regulates the normal position of the shoulder. If the stop-screws M be moved forward so as to come within the 20 plane of the stop-nut, the forward motions of the operating-lever will not affect the shoulder in any way whatever, and from an inspection of the drawings it will be seen that the 25 position of these stop-screws regulates the amount of movement to be given to the shoulder portion.

The rotatable mandrel may be mounted in any kind of a head-stock, and a bell-crank or other kind of lever used to engage with the 30 annular groove in the operating-sleeve to give such sleeve its forward and backward movements and consequently operate the parts.

I claim—

1. In a machine of the class described, the 35 combination of a rotatable mandrel, a forming-plug in the front portion thereof comprising a loosely-rotatable shell, and an arrow-head provided with one or more inclined rolls, substantially as described.

2. In a machine of the class described, the 45 combination of a rotatable mandrel, a forming-plug in the front part thereof, roll mechanism for forming the exterior of a bottle-neck, a parallel bar for each forming-roll 50 made in two parts, means for adjustably connecting the part carrying the forming-roll with the other part parallel to each other and to the mandrel, and means for moving the bar with its forming-roll toward or from the axis 55 of the rotatable mandrel, substantially as described.

3. In a machine of the class described, the 60 combination of a rotatable mandrel, a forming-plug in the front part thereof, roll mechanism for forming the exterior of a bottle-neck, a longitudinally-adjustable bar for each 65 forming-roll, means for moving the bar with

its forming-roll toward or from the axis of rotation of the rotatable mandrel, a shoulder portion for forming the lip of a bottle-neck provided with backwardly-extending arms arranged parallel with the rotatable mandrel and adapted to rotate therewith, a sliding disk or similar element secured to the shoulder-arms and adapted to be moved backwardly and forwardly, and an operating-sleeve for moving the disk or similar element with the shoulder portion backward and forward, substantially as described. 70

4. In a machine of the class described, the 75 combination of a rotatable mandrel, a forming-plug in the front part thereof, roll mechanism for forming the exterior of a bottle-neck, a parallel movable bar made in at least two sections, means for adjustably holding 80 the sections together, a shoulder portion surrounding the forming-plug provided with a backwardly-extending arm or arms, a disk or sleeve surrounding the rotatable mandrel and secured to the backwardly-extending arms of 85 the shoulder, and means for operating the disk or sleeve portion backwardly and forwardly and the forming-roll mechanism inwardly and outwardly, substantially as described. 90

5. In a machine of the class described, the 95 combination of a rotatable mandrel provided with a forming-plug in the front part thereof, a disk on the front portion provided with radial slots in the rotatable mandrel, roll mechanism for forming the exterior of a bottle-neck, a longitudinally-adjustable bar passed through the radial slots in the disk for adjustably holding and moving the forming-rolls backwardly or forwardly, a shoulder 100 portion for forming the lip of a bottle-neck provided with at least two arms bent backwardly therefrom, a sliding disk or similar element secured to the backwardly-extending arms of the shoulder portion, spring mechanism interposed between the slotted disk and the sliding disk to hold the shoulder in its normal back position, an operating-sleeve 105 slidably mounted on the rotatable mandrel, link mechanism interposed between the operating sleeve and the parallel-bar mechanism to operate the forming-roll mechanism inwardly and outwardly, a nut or collar on the rotatable mandrel to limit the backward movement 110 of the shoulder mechanism, and adjustable 115 screws in the sliding disk or similar element adapted to be contacted by the operating-sleeve and regulate the movements of the shoulder portion, substantially as described.
